UNITED STATES PATENT OFFICE.

EUGENE BUSWELL, OF WATERLOO, IOWA.

ACTUATING MEANS FOR WASHING-MACHINES.

1,121,796.

Specification of Letters Patent.

Patented Dec. 22, 1914.

Application filed October 27, 1913. Serial No. 797,584.

To all whom it may concern:

Be it known that I, EUGENE BUSWELL, a citizen of the United States of America, and a resident of Waterloo, Blackhawk county, Iowa, have invented certain new and useful Improvements in Actuating Means for Washing-Machines, of which the following is a specification.

My invention relates to improvements in actuating-means for washing-machines, and the object of my improvement is to simplify and render more convenient and inexpensive such means, while at the same time providing for the manual actuation thereof by the use of both hands of the operator. This object I have accomplished by the means which are hereinafter described and claimed, and which are illustrated in the accompanying drawings, in which:

Figure 1 is an elevation of my improved washing-machine. Fig. 2 is an upper plan view of said machine and that part only of the actuating-means which includes the two pull-cables and their operative connections to the pulley on the rock-shaft of the clothes-stirring body in the tub. Fig. 3 is an enlarged vertical axial section with parts broken away of said pull-cables, pulley-housing and pulley, and rock-shaft. Fig. 4 is an upper plan view of a similar mechanism to that shown in said Fig. 2, except that a pair of racks with an intermediate intermeshing gear-wheel are shown in place of the pull-cables and pulley of said other figure.

Similar numerals of reference denote corresponding parts throughout the several views.

A rock-body 16 provided with depending clothes-stirring pegs is shown in dotted lines only as mounted upon a vertical rock-shaft 1 within the tube 11. Said rock-shaft extends upwardly through an axial opening in the hinged cover 10 of said tube, with its upper end having a collar 2 removably secured on and supporting the same movably upon the top part of a hollow housing 3, the lower flanged-out part of the latter being secured about the axial opening of the cover 10 by means of bolts 4. Said cover 10 may be detachably secured to said tube 11 by means of a catch 15.

The numeral 6 denotes a pulley or sheave detachably secured upon the shaft 1 within said housing 3, the sheave being spaced in its upper part from said shaft to permit

of the extension thereinto of an integral cylindrical projection 5 of the housing 3, said projection being spaced from said shaft 1 to permit of the seating of a plurality of vertical rollers 9 therebetween to form an antifriction bearing for said shaft. The outer circumferential periphery is formed with two grooves for the cables 7 and 8, respectively, the ends of said cables being secured to the pulley in said grooves so as to wind and be seated therein. Openings are provided in the housing 3, to which the pull-cables 7 and 8 may be carried, and on the outer ends of said cables the blocks 12 are secured adjustably by means of set-screws 13. Said blocks 12 have integral pins 14 which may be movably seated and secured in bearing lugs on the hand-levers 17 and 18, respectively.

The numeral 19 denotes a bracket secured on one side of the tube 11 and having bearing openings to receive the fulcrumed pivot-pins 20 and 23, respectively, of the levers 18 and 17. The fulcrum of the lever 17 is located at its lower extremity, and said lever has at a short distance above said fulcrum 23 a short longitudinal slot 22 within which is slidably projected and seated a pin 21 extending from the lower extremity of the lever 18 below its said fulcrum 20. The movable connection permits of restricting the oscillations of the levers to cause them to have equal amounts of travel while being actuated. It will be seen that the operator may take said levers in both hands and reciprocate them in reversed directions simultaneously, with equal lengths of stroke, and in doing so impart by means of the pull-cables 7 and 8 rocking movements to the shaft 1 and its connected rocking-body 16 within the tub.

In Fig. 4, I have shown an equivalent device for rocking the shaft 1, which comprises a gear-wheel 27 mounted on said shaft 100 within the housing 3, the opposite sides of said housing being left open to permit of the passage thereby of the two racks 24 and 25, which intermesh the said gear-wheel. The numeral 28 denotes antifriction rollers 105 which are mounted to engage movably the outer sides of said racks 24 and 25 to retain the same in intermeshing contact with said gear-wheel 27.

The operation of the device is the same as that hitherto described, the integral pins 26 on said racks being pivotally connected to

the levers 17 and 18 in the same way that the bodies 12 are shown similarly connected to in said Fig. 1.

Having described my invention, what I claim as new and desire to secure by Letters Patent, is:

1. In combination, a rock-shaft rotatably mounted, and means for rocking said shaft to and fro, comprising a pair of pivoted hand-levers adapted to be oscillated in reverse directions simultaneously, a sheave mounted on said rock-shaft and having its upper part interiorly hollowed out from the top concentrically about the shaft, pull-cables connected between said hand-levers and said sheave to wind about the latter in opposite directions, a housing about said sheave having openings to permit of the passage of said cables, and having an integral depending hollow sleeve extending into said sheave about said shaft and spaced concentrically from the latter, rollers seated between, and in contact with the latter sleeve and said shaft to form an anti-friction bearing for the shaft, and a collar secured on the upper end of the shaft and

supporting the latter upon the top of said housing.

2. In combination, a rock-shaft rotatably mounted, and means for rocking said shaft to and fro, comprising a pair of pivoted hand-levers adapted to be oscillated in reverse directions simultaneously, a sheave mounted on said rock-shaft and having its upper part interiorly hollowed out from the top concentrically about the shaft, pull-cables connected between said hand-levers and said sheave to wind about the latter in opposite directions, a housing about said sheave having openings to permit of the passage of said cables, and having an integral depending hollow sleeve extending into said sheave about said shaft, and a collar secured on the upper end of the shaft and supporting the latter upon the top of said housing.

Signed at Waterloo, Iowa, this 11th day of Oct. 1913.

EUGENE BUSWELL.
